(57) **CLAIM**

The ornamental design for a bracket for a rack kit system, as shown and described.

DESCRIPTION

FIG. 1 is a perspective view of an exemplary embodiment of the bracket for a rack kit system showing my new design; FIG. 2 is a perspective view taken generally from the rear thereof;

FIG. 3 is a top plan view thereof;

FIG. 4 is an elevational view taken from the front thereof;

FIG. 5 is an elevational view taken from the left side with the

opposite side being a mirror image thereof;

FIG. 6 is an elevational view taken from the rear thereof; and,

FIG. 7 is a bottom plan view thereof.
